DESIGN FOR A COMBINATION ENVELOPE AND WRITING PAPER OR SIMILAR ARTI- CLE

Charles C. Dill, Sundown, Tex., assignor of one-fourth to Arthur R. Buzzard and one-fourth to Marteile Buzzard, both of Levelland, Tex.

Application February 5, 1943, Serial No. 109,464

Term of patent 3½ years

To all whom it may concern:

Be it known that I, Charles C. Dill, a citizen of the United States, residing at Sundown, in the county of Hockley and State of Texas, have invented a new, original, and ornamental Design for a Combination Envelope and Writing Paper or Similar Article, of which the following is a specification, reference being had to the accompanying drawing, forming a part thereof.

Figure 1 is a plan view of one side of a combination envelope and writing paper, prior to holding thereof and showing my new design.

Figure 2 is a plan view of the front of the combination envelope and writing paper shown in Figure 1, in folded position.

Figure 3 is a plan view of the opposite side thereof.

I claim:

The ornamental design for a combination envelope and writing paper, or similar article, as shown.

CHARLES C. DILL.
